DESIGN FOR AN INDEX CARD TAB

Harold J. Hoffman, Hastings, Minn., assignor to Peter A. Hoffman, Hastings, Minn.

Application July 9, 1943, Serial No. 110,634

Term of patent 14 years

To all whom it may concern:

Be it known that I, Harold J. Hoffman, a citizen of the United States, residing at Hastings, county of Dakota, and State of Minnesota, have invented a new, original, and ornamental Design for an Index Card Tab, of which the following is a specification, reference being had to the accompanying drawing, forming part thereof, and in which

I claim:

The ornamental design for an index card tab, substantially as shown.

HAROLD J. HOFFMAN.
